UNITED STATES PATENT OFFICE.

WALTER A. O'BANNON, OF TULSA, OKLAHOMA.

MULTIPLE SUCKER-ROD SOCKET.

Application filed April 21, 1926. Serial No. 103,601.

The present invention relates to the art of fishing tools, and especially to that class known more generally as sucker rod sockets. These improvements have particular reference to the multiple type of implement designed to catch and pull broken sucker rods of various sizes from deep wells, and the primary objects in view are to provide a tool of this character embodying simplicity of construction conducive to economy of manufacture, greater durability in use, and an arrangement of slip wedges such that replacement may be readily made of those gripping elements subject to greatest wear and breakage with a resultant saving as against replacement of the whole.

In sucker rod sockets of the multiple type there is usually provided a plurality of slips or slip sections, one for use in catching rods which have been broken at the joint or enlarged portion, and another for use where the rod is broken between the joints. Such an arrangement is characteristic of the present invention. Each of these sections is split in a longitudinal direction into a plurality of segments the contraction of which upon the rod is produced by the taper formation of the barrel or bowl in which they are mounted. I do not herein claim such a construction broadly since it is the purpose of these improvements to provide means co-acting with the sections and parts thereof such that while each section is capable of expanding and contracting freely and independently they are caused to move together as a unit in their upward and downward movements and the parts thereof prevented from longitudinal movement with respect to each other.

Other objects and advantages of the invention will be hereinafter set forth and the novel features thereof defined by the appended claims.

In the accompanying drawing:

Figure 1 is a vertical sectional view through the lower portion of a sucker rod socket showing the preferred form of slip unit;

Figure 2 is a transverse sectional view on the line 2—2 of Figure 1; and

Figures 3, 4 and 5 are fragmentary sectional views of slip units showing slightly modified forms of the connector piece employed to conjoin the sections of the slip unit.

Like reference characters designate cor-

responding parts throughout the several figures of the drawing.

Referring to the drawing, 1 designates the barrel of the sucker rod socket, the lower portion only of which is shown. As disclosed in Figure 1, the barrel tapers internally toward the bottom as indicated at 2, the entrance to said barrel preferably being beveled at 3 to facilitate the operation of "finding".

Within the barrel is mounted the slip unit which is composed of what, for the purposes of this description, I term the lower or box section 4 and the upper or rod section 5. 70

Exteriorly these sections are formed on a continuous uniform taper conforming to the taper of the barrel, and internally each is provided with a tapered bore, that of the box section being of greater diameter than the bore of the rod section. As a matter of practice the bores of the two sections are substantially continuous and are provided with the usual wickers 6 and 7 respectively. Furthermore, each of the sections is split 80

longitudinally one or more times along the lines 8 so as to provide for expansion and contraction as the slip unit is moved upwardly and downwardly respectively in the tapered bore of the barrel. Obviously a slip 85 construction of this type is advantageous because of the ability to use the same to catch rods of different diameters, but a feature which is particularly important from the manufacturing standpoint resides in the 90

ability to heat treat the sections to much better advantage because of the substantial uniformity of their thicknesses. Heretofore in devices of this character, owing to the taper of the external and internal walls, the 95

thickness of the metal at the top was so much greater than the thickness at the bottom that it was practically impossible to temper one section without over or under tempering the other. This is especially important in view 100

of the fact that owing to the thinness of the box section and the tremendous strain imposed upon it in use, it must be tempered to the proper degree or frequent breakage will result. In the majority of instances, this means discard of the complete slip unit but by virtue of the provision of separate slip sections any breakage or wear of one may be replaced without the loss of the other. Further than this, such an arrangement of 105

separable sections in the slip unit enables the use of different sets of slips adapted for

varying makes of boxes. As a matter of fact, it is within the purview of this invention to replace the box section by one designed to catch a plain rod in which event the size of 5 the wickered bore is necessarily materially reduced.

I now pass to the feature of my present invention which is the particular subject matter of this application, namely the 10 means employed for conjoining or connecting the box and rod sections together so that they will move as a unit in all longitudinal movements of the slip body while allowing for freedom of independent expanding and 15 contracting movements of the parts. In the preferred form of Figure 1 this means consists of an annular member or ring 9 surrounding the contiguous bores of the sections and having an upper flange 10 engaging in the annular groove 11 in the rod section and a lower flange 12 seated in a corresponding annular groove 13 of the box section. It will be noticed that by virtue of the disposition of this ring internally of 20 the slip body, as shown in Figures 1, 3 and 5, it not only acts to connect the two sections together so as to cause them to move together in the up and down travel of the slip unit and prevents the relative longitudinal 25 movements of the parts of said sections, but it acts also as a guide for directing the rod to be gripped into the bore of the upper section. Likelihood of the end of the rod catching on the lower edge of 30 the upper section is thereby precluded. The bore of the ring, it will be observed, is preferably formed on a taper so as to conform with the taper of the slip sections at the juncture of the same. As shown in Figures 35 3, 4 and 5 this ring connector may take different forms, that depicted in the first named figure and designated 9 being substantially the same except for the intermediate flange 9^b which extends outwardly 40 between the upper and lower sections. In Figure 4 the ring 9^c is externally applied and of U-shaped cross section, while the ring 9^d of Figure 5 is S-shaped in cross section so that half is internally disposed and half 45 externally disposed. Any or all of these rings may be split to facilitate their application to the section.

Having thus described my invention, what I claim as new is:—

55 1. A slip unit for sucker rod sockets composed of upper and lower sections, and separate annular means surrounding the contiguous ends of the sections for connecting

one to the other for vertical movement together but permitting relative independent movement laterally.

2. A slip unit for sucker rod sockets composed of separable sections, each section consisting of an independently operative set of gripping members, and a separate connector 65 common to the members of said sections for holding them in assembled position when in a socket while permitting relative free expansion or contraction movement.

3. A slip unit for sucker rod sockets composed of superposed sections and annular means having tongue and groove connections with said sections.

4. A slip unit for sucker rod sockets composed of separable superposed sections, and 75 a ring member engaging about the juncture of said sections, each of said sections being formed with a groove to receive the ring.

5. A slip unit for sucker rod sockets consisting of a rod section and a box section, 80 and a separate connector member for bridging the adjacent ends of the two sections and constituting a guide assisting in passing an object from one section to the other while permitting free expansion or contraction of 85 one section relative to the other.

6. In a sucker rod socket, the combination of a barrel having a tapered bore, a slip unit mounted in said bore and composed of a rod section and an independent box section, and loosely fitting annular means disposed about the juncture of the two sections for holding the same in contiguous relation, each of said sections being free to independently expand and contract under the 95 control of the tapered portion of the barrel.

7. A slip unit for sucker rod sockets composed of separable sections, each section comprising an independently operative set of gripping members, and a separate connecting means embracing the adjacent ends of said sections for holding them in assembled relation when in a socket while permitting relative free expansion or contraction movement.

8. A slip unit for sucker rod sockets composed of separable sections, each section comprising an independently operative set of gripping members, and a connecting member seated at its opposite ends in the adjacent 100 sections to overlap the joint therebetween and provide for the independent movement of the sections and a guiding face from one section to the other.

In testimony whereof I affix my signature.
WALTER A. O'BANNON.
